UNITED STATES PATENT OFFICE.

ALGER S. VOIGHT, OF JOLIET, ILLINOIS.

TRANSMISSION BAND FOR AUTOMOBILES.

1,417,870.

Specification of Letters Patent. Patented May 30, 1922.

Application filed June 20, 1921. Serial No. 478,842.

To all whom it may concern:

Be it known that I, ALGER S. VOIGHT, a citizen of the United States, residing at Joliet, in the county of Will and State of Illinois, have invented certain new and useful Improvements in Transmission Bands for Automobiles, of which the following is a specification.

This invention relates to transmission bands of the kind commonly used in certain types of automobiles in which a split or divided band encloses a drum forming part of the transmission mechanism. Ordinarily such bands comprise a split steel band or ring adapted to closely surround a drum and which carries at its free ends shoes connected by a spring-carrying rod, operated by a pedal in such manner that when the pedal is depressed the band is tightened on the drum and holds the latter against rotation. In such mechanism as heretofore constructed the strain is not equally distributed and there is a difference in wear at different parts of the band.

According to my invention I provide means whereby these differences in wear are avoided. To do this I provide a supplemental band which partially surrounds the ordinary band, and I interpose springs between the two bands which are so located as to exert pressure at different parts of the band and thus distribute the strain and wear. One end of the inner band is secured to a shoe, of usual construction, while the companion shoe is attached to the outer end of the outer or supplemental band, the opposite end of this outer band being detachably connected with the inner band. The outer end of the inner band extends into a guide carried by the inner band.

In the accompanying drawings—

Figure 1 is a perspective view of a transmission band embodying my improvements, showing its connection with the pedal arm. Figure 2 is a side elevation of the band, the lining being omitted.

Figure 3 is an end view of the band shown in Fig. 2.

The inner band A carries at one end a shoe B of usual construction, and at its opposite end it carries a guide C for the outer end of the inner band. The outer or supplemental band D partially surrounds the inner band. Its inner end is detachably connected to the inner band at d. The opposite end of the outer band carries a shoe E which extends into the guide C between

the sides e thereof. Springs F are interposed between the two bands. These are preferably steel leaf springs and are attached to the inner band at f and they have curved or arched portions bearing against the outer band. Any suitable number of springs may be employed and they may be located at suitable distances apart to distribute the strain. The inner band may be suitably lined, as indicated, at L.

The ears b, c of the shoes B and E are slotted, as shown, to receive the rod H carrying a spring h, as usual, and which is secured to one cam member m which cooperates with another cam member m' operated by a pedal M.

When the pedal is operated the shoes B and E approach each other, the shoe E sliding in the guide C and at the same time the outer band is drawn closer to the inner band compressing the springs F and applying the strain equally and yieldingly to the drum. In this way, as experience has demonstrated, the wear on the band is made uniform and the strain is cushioned and made more efficient.

While the invention is especially intended for use as a transmission band in the manner before described, it may also be used as a brake in an obvious way.

I claim as my invention:—

1. A transmission band for automobiles, comprising an inner band carrying at one end a shoe and at the opposite end a guide, an outer band detachably connected at one end to the inner band and carrying at its other end a shoe which enters the guide, springs interposed between the two bands at intervals and tending to separate the same, and means for drawing the shoes toward each other and thereby applying pressure through the springs to the inner band.

2. A transmission band for automobiles, comprising an inner band extending substantially around a drum, and which carries a shoe at one end and a guide at the other end, an outer band of slightly less length detachably connected at one end to the inner band and carrying at its other end a shoe that fits in said guide, springs interposed between the two bands at intervals and carried by the inner band, and means engaging the shoes for applying pressure to the inner band through said springs.

In testimony whereof, I have hereunto subscribed my name.

ALGER S. VOIGHT.
